UNITED STATES PATENT OFFICE.

MARCELLUS A. MORSE, OF CHICAGO, ILLINOIS, AND THEODORE G. SPRINGER,
OF NEW YORK, N. Y.

PROCESS OF AND APPARATUS FOR MANUFACTURING GAS.

SPECIFICATION forming part of Letters Patent No. 411,389, dated September 17, 1889.

Application filed August 20, 1887. Serial No. 247,471. (No model.)

To all whom it may concern:

Be it known that we, MARCELLUS A. MORSE and THEODORE G. SPRINGER, citizens of the United States, residing, respectively, at Chicago, in the county of Cook and State of Illinois, and at New York city, in the county and State of New York, have invented new and useful Improvements in the Process of and Apparatus for Manufacturing Gas, of which the following is a specification.

This invention relates to the manufacture of illuminating-gas in cupola generating-furnaces, and more particularly to the economical method and means for carbureting, combining, and fixing water-gas; also to improvements in the construction of the cupola generating-furnace, whereby it may be more readily charged with fuel and cleared of clinker.

The object of the invention is to economically manufacture high-grade illuminating-gas by first producing low-grade fuel-gas, known as "producer-gas," from cheap fuel—such as bituminous coal, slack, or other low-priced material—and by means of such gas heating up a combining and fixing chamber containing refractory material—such as fire-brick—and then utilizing the heat stored in the refractory material for vaporizing hydro-carbon liquid and combining the vapors with water-gas and converting the mixture into a fixed illuminating-gas.

While low-grade fuel—such as cheap bituminous coal or slack—can be advantageously used to make producer-gas, which can be burned while hot to heat an oil-vaporizing and gas-fixing chamber, such fuel is not adapted for decomposing steam to make water-gas, since it cakes and runs together under the high heat in such manner that steam will not pass through it, and, besides, it contains too large a percentage of sulphur and other impurities to yield a desirable quality of water-gas. We therefore burn only that

quantity of high-priced hard anthracite coal or hard coke in the water-gas generator which is required to heat such body of coal to incandescence and heat the steam-superheating chamber above, the waste gaseous products arising from the high-grade coal or

hard coke while blasting with air being utilized for heating such steam-superheating chamber, and in order to properly heat the oil-vaporizing and gas-fixing chamber we utilize the low-grade cheap fuel heretofore mentioned, thus effecting an important saving of expensive fuel and lessening the cost of manufacturing illuminating-gas. The hard coal or coke required for decomposing steam is adapted to be rapidly blasted with a strong air-blast for quickly heating it to incandescence after it has been deadened by the passage of steam through it for decomposition, and we are thus enabled to quickly heat it up after a run for making water-gas, though no more of such fuel is burned than is required for heating the steam-superheating chamber. We are, however, able to use with much economy low-grade cheap fuel, which can only be burned slowly at a comparatively low temperature for heating the combining and fixing chamber, as such chamber is necessarily heated only to a moderate temperature, so that it will convert the hydrocarbons into fixed gas without burning them into lamp-black. Moreover, such low-grade fuel is not deadened by the passage of steam through it, and can therefore be kept alive and be gasified with slow combustion and at a comparatively low temperature. Our invention includes the operations, as described, with both kinds or qualities of fuel, whereby greater economy is effected in the manufacture of illuminating-gas.

Another object of the invention is to provide for more conveniently and evenly charging the fuel and decomposing chamber with fuel and clearing it of clinker which collects and adheres to the side walls.

The accompanying drawing illustrates a vertical section of a pair of our improved cupola generating-furnaces properly connected and arranged for carrying out our process of manufacturing illuminating-gas.

The two cupola-furnaces M N are constructed substantially alike, with slight differences in the connections of pipes for steam and gas, the right-hand cupola (lettered M) being arranged for superheating and decomposing steam to form water-gas, and the one to the

left (lettered N) being arranged to vaporize hydrocarbon oil and combine it with water-gas to form a fixed illuminating-gas. They are constructed with fuel-chambers A A' 5 at the base and the steam-superheating chamber C and the oil-vaporizing and gas-fixing chamber C' at the top, the upper and lower chambers being separated by arched brick partitions B B', having passages a a'. Chambers C C' are filled with refractory brick or tile c c', preferably laid in high courses at right angles to each other. Combustion-chambers w w' are provided immediately above the arches B B', and secondary combustion-chambers y y' are provided above between 15 the courses of brick. These combustion-chambers have annular air-supply flues U U' and ports u u'. Air-supply pipes T' T'', having valves t t', connect with the annular flues of chamber C, and air-supply pipes V' V'', having valves v v', connect with the annular flues of chamber C'. Pipes X X', having tight-fitting lids x x' for the escape of products of combustion, connect with the tops 25 of chambers C C'.

The fuel-chambers A A' are of peculiar and improved construction. They are made to project laterally at the top beyond the vertical walls of the superheating and fixing chambers above. The top G of the projecting portion joins the main vertical walls of chambers C C' at or near the division-arches B B', and such top is provided with passages I, closed by tight lids b b, for feeding in the fuel at 30 two or more points in the circumference, so that it may be evenly distributed, and for inserting clinkering-bars to detach clinker adhering to the side walls down in the fuel-chambers and properly adjust the fire. The 35 side walls are preferably made flaring from the base of the fuel-chamber up to the top G, so that they may be effectually cleaned by bars inserted in the downwardly-extending passages I. The fuel-chambers extend at their lower ends m n down into the base-chambers D D', occupying the place of the usual ash-pit. These chambers have each tight-fitting 40 doors d and d' on opposite sides of the furnace. The extension of the fuel-chamber is 45 formed by the brick side walls of chamber D and the inclined bars E, extending across chamber D. The top cross-bars e of bars E are set in the brick walls a short distance below the top of chambers D D', so as to leave 50 spaces for inserting temporary false bars to support the body of fuel above when clearing the ashes and clinker from the extensions m n below. Base-blocks F, of iron or brick, and which may be provided with passages 55 on a line with doors d d', rest upon the floors of chambers D D' for supporting the fuel. Air-blast pipes T V connect with chambers D D'. At the top of chamber C connect steam-supply pipe S, having valve s, and oil-supply 60 pipe O, having valve o. An oil or vapor supply pipe P, having valve p, connects with the top of the chamber C'. The gas take-off pipe 65

H for water-gas connects with chamber D of cupola M, passing a short distance through the walls of the fuel-chamber, and is provided with a valve h. Gas-pipe L connects with pipe H and extends up through the brick wall of chamber C' in cupola N, and opens into the top of chamber C', where it supplies hot water-gas. The take-off pipe for illuminating-gas leads from chamber w' in the base 70 of chamber C'. 75

The operation is as follows: Fires are kindled in the fuel-chambers A A' of cupolas M M', and they are supplied with fuel till deep 80 bodies of fuel are well ignited, the lids x x' being open. Air-blasts are admitted to the bodies of fuel and also to chambers w w' and y y' for burning the gaseous products arising from the fuel till chambers C C' and 85 the contained brick-work are heated to the desired temperature for superheating steam and for vaporizing oil and converting it into a fixed gas with the water-gas. Cheap fuel—such as bituminous coal or slack—is 90 supplied to chamber A' so as to make what is known as "producer-gas," which is of suitable quality for heating up the oil-vaporizing and gas-fixing chamber C'. Hard anthracite coal, or hard coke of high grade, is 95 supplied to the steam-decomposing chamber A, so as to make a good quality of water-gas. The chambers C C' being properly heated and the body of fuel in chamber A being raised to incandescence, the air-blasts are shut off, 100 lids x x' are closed, valve h is opened, and steam is admitted by pipe S into chamber C, where it is highly superheated by passage down in contact with the heated brick-work. The superheated steam is decomposed into 105 hydrogen and carbonic oxide by passage down through the incandescent fuel in chamber A, and these gases pass while hot through pipes H L into the top of chamber C', into which at the same time hydrocarbon oil or vapor is admitted by pipe P in sufficient quantities to carburet the water-gas and form illuminating-gas of the desired candle-power. The oil flows down over the heated brick-work into a gradually-increasing temperature till it is all 110 vaporized. The oil-vapors are combined with the hot-water gas and in the hotter portions of the chamber C' are converted into a fixed 115 illuminating-gas, which flows off through the pipe K. At the time of admitting steam into 120 chamber C a small supply of hydrocarbon oil is also admitted into such chamber in suitable quantity to supply one equivalent of carbon to two equivalents of oxygen in the steam, whereby mutual decomposition of the 125 oil and steam will take place to form carbonic-acid and hydrogen gases. These gases, together with any remaining undecomposed steam, pass into the body of incandescent fuel, where the carbonic acid is converted into 130 carbonic oxide and the steam is decomposed into hydrogen and carbonic oxide. The manufacture of gas is continued, as above described, till the temperature of the chambers 130

is too much reduced for effective operation, when the steam and oil are shut off and the chambers C C' and body of fuel in chamber A are reheated, as above described, for again 5 making gas.

In the operation of reheating the apparatus producer-gas is again made in chamber A' and burned in chamber C' for heating it.

Having described our invention, what we 10 claim, and desire to secure by Letters Patent, is—

1. The process of manufacturing gas, which consists in highly heating a body of high-grade hard coal or coke by rapid combustion 15 and burning the resulting gaseous products with air and storing the heat in a body of refractory material, and at the same time burning a body of slack or low-grade cheap fuel with a slow combustion, and by means of the 20 resulting gaseous products heating a second body of refractory material, then suspending the combustion, then superheating steam by passing it through the body of refractory material heated by the waste gaseous products 25 of the hard coal or coke, then decomposing such steam by passing it through the body of incandescent hard coal or coke, and then passing the resulting gases, together with a hydrocarbon, through the body of refractory material 30 previously heated by the gaseous products arising from the low-grade fuel for producing a fixed illuminating-gas.

2. The process of manufacturing gas, which consists in raising a body of hard coal or coke 35 to a state of incandescence by rapid combustion with air, burning the resulting gaseous products with air and storing the heat in a body of refractory material, and at the same time heating a second body of refractory material by the combustion of gaseous products 40 arising from a separate body of cheap low-

grade fuel, then suspending the process of combustion and passing a hydrocarbon, with steam in excess, through the body of refractory material heated by the waste products 45 of combustion of the hard coal or coke, decomposing the steam into carbonic-acid and hydrogen gas, then passing such gases through the incandescent hard coal or coke to convert the carbonic-acid gas into carbonic 50 oxide and the hydrogen into light carbureted hydrogen, and then passing the carbonic oxide and carbureted hydrogen, together with sufficient hydrocarbon to make an illuminating-gas, through the second body of refractory 55 material previously heated by the gaseous products from the low-grade fuel, whereby the hydrocarbon is converted into fixed illuminating-gas.

3. A cupola gas-generator having a fuel-chamber and a fixing-chamber, both in one structure, as described, the walls of the fuel-chamber being constructed to flare from below upward and outward and project at the top circumferentially outward beyond the 65 base of the fixing-chamber, and said projecting portion having one or more openings passing downward through its top and in line with the flaring walls, through which openings the fuel-chamber may be evenly charged 70 with fuel and the clinker readily cleaned from the walls, and said openings being provided with tight-fitting lids, as described.

In testimony that we claim the foregoing as our invention we have signed our names, in 75 presence of two witnesses, this 9th day of August, 1887.
